UNITED STATES PATENT OFFICE.

LOUIS EDMOND SOLIGNAC, OF PARIS, FRANCE.

STEAM-GENERATOR.

SPECIFICATION forming part of Letters Patent No. 560,286, dated May 19, 1896.

Application filed May 2, 1895. Serial No. 547,840. (No model.) Patented in France October 18, 1894, No. 242,194.

To all whom it may concern:

Be it known that I, LOUIS EDMOND SOLIGNAC, of the city of Paris, France, have invented Improvements in Steam-Generators, 5 (for which I have obtained Letters Patent in France for fifteen years, dated October 18, 1894, No. 242,194,) of which the following is a clear and exact description.

This invention relates to steam-generators 10 of the kind in which highly-heated water injected into a heated tube is flashed into steam, the invention consisting more particularly in the combination and arrangement of the various parts, as will be hereinafter described. 15 In a steam-generator of this kind the length of the flashing-tube should be as restricted as possible; otherwise there would be too great a difference in the evaporative effect at successive parts of the tube, those nearest the jet 20 being bathed in water, while those near the exit evaporate, whereas if the injection be reduced the latter will only superheat. Now the great evaporative power (two hundred kilos per square meter) of such steam flashers 25 or generators depends upon the fact that their heating-surfaces are not, as in ordinary generators, completely covered with water, which being a bad conductor of heat impedes the transmission to the operative surface of the 30 water of the heat received at the heating-surface. The thinner the layer of water between the heating and evaporative surfaces the more rapid will be the evaporation, which reaches its maximum when the heating and 35 evaporative surfaces are coincident, as in a heated tube into which water is injected. Therefore, when a portion of the tube merely superheats the steam, the surface is but imperfectly utilized, inasmuch as superheated 40 steam only absorbs about one caloric per kilogram, from which it will be evident that it is of advantage to limit the length of the tube. When, therefore, it is required to evaporate a large quantity of water, a number 45 of such steam-flashing tubes should be employed, placed parallel to one another, instead of a single one of greater length. It is known that in ordinary generators the elasticity of production depends on the volume of water 50 superheated. I have also found that to avoid overheating it is only requisite to inject un-

der pressure water at the highest possible temperature, which partly evaporates, moistens the surface of the tube with steam, and thus insures the contact of the non-vaporized 55 liquid with the heated surface.

Figure 1 shows a developed section of a device embodying my invention, the same being a vertical section through the reservoir and pipes and a horizontal section through 60 the flasher-tubes; and Fig. 2, a vertical section through the flasher-tubes on lines 1 2 of Fig. 1.

The generator comprises a series of horizontal tubes *a*, placed within a furnace and 65 heated directly therefrom. Into the lower end of each tube projects a nozzle *b*, by which water is injected in the form of spray, the nozzles *b* being supplied by a pump *d*, which takes the water from the boiler *e* and delivers 70 it under pressure through pipe *c*, the pump being actuated by a donkey-engine *h*, supplied with steam by pipe *i* from the steam-space of the boiler *e*, which contains a large supply of water heated under pressure by the steam 75 generated in the flashing-tubes *a*, which are connected to the boiler by pipes *f*, provided with check-valves *g*, allowing the steam to enter the lower part of the boiler and pass up through the water therein, but preventing the 80 return of water. *j* is the steam-pipe of the boiler. A pipe *k* connects the boiler *e* and the pipe *c* for establishing circulation at starting before any steam is available for working the donkey-engine, a cock on said pipe being 85 closed when the pump is started.

The advantages of the above-described arrangement are reduction of the heating-surface required, inasmuch as evaporation is effected by injection under the most favorable 90 conditions, regard being had to the short length of the tubes; avoidance of overheating while using tubes of large area to promote the generation of steam and consequently rapid evaporation; elasticity of production not less 95 than in ordinary boilers, the large body of water contained in the boiler *e* serving as a reservoir; freedom from risk of accident as each flashing-tube is made independent by its check-valve *g*, and but a small volume of 100 water is injected at a time. As the boiler *e* need not be directly heated by the flames it

may be considered to be not a boiler, but simply a reservoir or steam-chest.

The number and mode of grouping the flashing-tubes may be varied according to the 5 quantity of steam to be produced, said tubes being always independent either individually or in groups working in parallel under similar evaporative conditions.

I claim—

- 10 1. In a steam-generator, the combination of a reservoir, flasher-tubes located below the reservoir and leading thereto, provided with nozzles at their lower ends and inlet-valves leading into the reservoir interposed between the tubes and the reservoir the said inlet-15 valves being arranged to admit the inflow of steam therethrough into the reservoir and to

check the outflow of water therethrough, substantially as described.

2. In a steam-generator, a reservoir, flasher-tubes located below the reservoir, nozzles in the lower ends of the tubes fed from the reservoir and discharging into the tubes, and valved communication between the upper ends of the tubes and the reservoir, forming 20 the steam-conduits between the tubes and the reservoir, substantially as described.

The foregoing specification of my improvements in steam-generators signed by me this 17th day of April, 1895.

LOUIS EDMOND SOLIGNAC.
